(57) **CLAIM**

The ornamental design for an electrosurgical generator, as shown and described.

DESCRIPTION

FIG. 1 is a top front perspective view of an electrosurgical generator, showing our new design;

FIG. 2 is a top rear perspective view of the electrosurgical generator of FIG. 1;

FIG. 3 is a top plan view of the electrosurgical generator of FIG. 1;

FIG. 4 is a bottom plan view of the electrosurgical generator of FIG. 1;

FIG. 5 is a right side elevational view of the electrosurgical generator of FIG. 1;

FIG. 6 is a left side elevational view of the electrosurgical generator of FIG. 1;

FIG. 7 is a front elevational view of the electrosurgical generator of FIG. 1;

FIG. 8 is a rear elevational view of the electrosurgical generator of FIG. 1;

FIG. 9 is a top front perspective view of an alternate embodiment of an electrosurgical generator;

FIG. 10 is a top rear perspective view of the electrosurgical generator of FIG. 9;

FIG. 11 is a top plan view of the electrosurgical generator of FIG. 9;

FIG. 12 is a bottom plan view of the electrosurgical generator of FIG. 9;

FIG. 13 is a right side elevational view of the electrosurgical generator of FIG. 9;

FIG. 14 is a left side elevational view of the electrosurgical generator of FIG. 9;

FIG. 15 is a front elevational view of the electrosurgical generator of FIG. 9; and,

FIG. 16 is a rear elevational view of the electrosurgical generator of FIG. 9.

The broken lines immediately adjacent the shaded areas represent the bounds of the claimed design while all other broken lines are directed to environment and are for illustrative purposes only; the broken lines form no part of the claimed design.
